UNITED STATES PATENT OFFICE.

GEORGE BAEHR, OF MCKEESPORT, PENNSYLVANIA, ASSIGNOR TO CUTLER-HAMMER MFG. CO., OF MILWAUKEE, WISCONSIN, A CORPORATION OF WISCONSIN.

ELECTRIC SWITCH.

1,222,714.

Specification of Letters Patent.

Patented Apr. 17, 1917.

Application filed October 8, 1908, Serial No. 456,742. Renewed October 29, 1913. Serial No. 798,136.

To all whom it may concern:

Be it known that I, GEORGE BAEHR, a citizen of the United States, residing at McKeesport, in the county of Allegheny and State of Pennsylvania, have invented new and useful Improvements in Electric Switches, of which the following is a full, clear, concise, and exact description, reference being had to the accompanying drawings, forming a part of this specification.

My invention relates to improvements in electric switches or contactors.

One object of my invention is to provide a switch or contactor which will be compact in structure, durable and efficient in operation.

A further object is to provide a switch of such construction that the parts thereof may be readily assembled.

Other objects and advantages of my invention will be hereinafter set forth.

In order to more clearly set forth the characteristics of my invention I have shown, in the accompanying drawings, a switch which I have worked out in practice.

The views in the drawings are as follows:

Figure 1 is a front elevation of the switch, and

Fig. 2 is a vertical sectional view taken therethrough.

The several parts of the switch are carried by a frame which is preferably cast and is provided with a hollow rectangular portion 1, and two upwardly extending parallel side pieces 2. Extending laterally from the rectangular portion 1 of the frame are two lugs 3—3, and extending laterally from the side pieces 2—2 are lugs 4—4. The lugs 3 and 4 provide means whereby the frame may be bolted, or otherwise secured to a suitable supporting panel 5. Mounted within the rectangular portion 1 of the frame, is an electromagnetic winding 6. The winding 6 is preferably wound upon a fiber tube 7 which is provided at its ends with annular flanges 8—8. The winding 6 is held in place by a core or plug 9 which extends through an orifice in the top of the rectangular portion 1 of the frame and fits within the fiber tube 7. The core or plug 9 is provided at its end with an annular flange 10 which rests upon the top of the frame 1. The flange 10 is recessed to receive an elastic buffer 11. Mounted within the fiber tube 7, and arranged to slide freely therein, is a plunger 12 which carries at its upper end a rod 13 of non-magnetic material. The rod 13 extends through the plug 9 and carries, adjacent to its upper end, a flange or collar 14 which is adapted to bear against the elastic buffer 11 to limit the downward movement of the plunger 12. The upper end 15 of the rod 13 is rounded and works in a cup-shaped recess in a bearing block 16, set into the underside of the contact arm 17. Set into the upper side of the switch arm 17, adjacent to its rear end, is a bearing block 18, the bearing face of which is curved and is adapted to bear against a pin 19, supported between the side pieces 2 of the frame. Secured to the front of the rectangular portion 1 of the frame by screws 21, is an insulating block 20 preferably formed of fiber. Secured at one end to an eye-bolt 22 on the fiber block 20, and at its other end to an eye-bolt 23 on the forward end of the switch arm 17, is a tension spring 24. Inasmuch as the switch arm 17 is supported on the end of the rod 13, the spring 24 tends to draw the forward end of the arm 17 downwardly and to force the bearing block 18 firmly against the pin 19. This arrangement provides an open bearing for the switch arm 17, and consequently, the switch arm will require little or no lubrication. The upright pieces 2 of the frame carry inwardly extending projections 25 between which the switch arm 17 is free to move vertically, but which prevent lateral movement thereof. Adjacent to its rear end, the arm 17 is provided with a binding-post 26 to which is secured one end of the conductor 27. The opposite end of the conductor 27 is secured to a binding-post 28 carried by the frame and suitably insulated therefrom. The binding-post 28 forms one terminal of the switch. The arm 17 carries a main contact plate 29 which is preferably secured thereto by screws 30. At its forward end, the arm 17 is provided with bifurcated portions 31 which are curved to form a ring. Passing through the ends of the bifurcated portions 31 is a screw 32, the purpose of which will be hereinafter explained. The ring formed by the bifurcated portions 30 is internally screw-threaded and adapted to receive a screw-threaded cylindrical arcing contact 33. The arcing contact 33 is preferably provided with notches 110

34 adapted to receive a suitable instrument for turning same to raise or lower it on the arm 17. When the contact 33 has been properly adjusted, the bifurcated portions 31 are drawn together by means of the screw 32 to firmly clamp said contact. Mounted in inclined grooves or guides 35, provided in the upright members 2 of the frame, is an insulating block 36. The block 36 is preferably formed of fiber and is held in place by means of a bolt 37 which passes therethrough and also through the upright pieces 2 of the frame. The bolt 37 is held in place by nuts 38. Secured to the upper face of the block 36 by bolts 40 is a frame 39 which is provided with a brush holder 41 and two forwardly extending arms 42. The frame 39 preferably comprises a brass casting. The brush holder 41 preferably comprises a yoke in which is mounted a contact brush 43. The brush 43 preferably comprises a plurality of laminations so arranged that the ends thereof will be engaged by the main contact plate 29 on the switch arm 17 when the same is raised to the position illustrated. Interposed between the brush 43 and the yoke 41 are suitable clamping plates 44 against which bears the end of a set-screw 45 which holds the brush in place. The set-screw 45 provides means whereby the brush may be properly adjusted in the holder to insure a good contact with the main contact plate on the arm 17. With this arrangement the brush 43 may be reversed when one end of the same becomes worn out. The set-screw 45 carries a jam-nut 46 which is adapted to be forced against the top of the brush holder to prevent said set-screw from loosening. The extensions 42 of the frame 39 are formed into a ring adapted to receive a cylinder 47. Extending through the ends of the extensions 42 is a screw 48 by means of which the cylinder 47 may be firmly clamped between the extensions 42. The cylinder 47 is internally screw-threaded to receive a screw-threaded plug 49. Mounted within the cylinder 47 is a piston 50 provided with a partially screw-threaded stem 51 which passes through an orifice in the plug 49. Mounted upon the screw-threaded portion of the stem 50 are a pair of nuts 52 between which is clamped one end of conductor 58. The opposite end of the conductor 58 is secured by a bolt 59 to one of the extensions 42 of the frame 39. The underside of the plunger 50 is recessed to receive a carbon contact block 57 adapted to be engaged by the arcing contact 33 carried by the switch arm 17. The downward movement of the plunger 50 is limited by an internal bead 56 on the cylinder 47. Interposed between the plunger 50 and the plug 49 is a coil spring 53 which tends to force the plunger and carbon contact downwardly. While the spring 53 permits the carbon contact 57 to yield under the pressure of the arcing contact 33, yet it tends to force the carbon contact firmly into engagement with the arcing contact. The desired pressure between these contacts may be obtained by adjusting the arcing contact on the arm 17 and by adjusting the plug 49 in the cylinder 47. Secured to the front of the insulating block 20, by bolts 60, are pole-pieces 61 of a blow-out coil 62. The pole-pieces 61 extend upwardly on opposite sides of the arcing contacts 33 and 57. The upper ends of the pole-pieces 61 form polar faces between which runs the magnetic flux produced by the blow-out coil 62. Between these polar faces is arranged an insulating chute or barrier, which comprises side-pieces 63 and a connecting piece 64 which is arranged parallel to the magnet 62. The side-pieces 63 shield the arcing contacts from the polar faces and are secured to the horizontal piece 64 which is supported on rods 65 passing through the pole-pieces 61. Passing through the lower ends of the pole-pieces 61 is a bolt 66 which carries the core 67 of the blow-out coil. Between the blow-out coil and the core 67 is interposed an insulating tube 68 and between the ends of said coil and the pole-pieces are interposed insulating disks 69. One end of the blow-out coil 62 is secured and electrically connected by bolts 70 to one side of the frame 39 which carries the main contact 43 and which is electrically connected to the carbon contact 57. The opposite end of the blow-out coil is secured in a terminal block 71 by screws 72. The terminal block 71 is secured to the front of the fiber block 20 by screws 73. The heads of the screws 73 are preferably countersunk in the terminal block 71. The terminal block 71 may be provided with a binding-post or may be connected by a conducting bar to the terminal block of another switch. By arranging the blow-out coil beneath the switch members the same is removed from the path of the arc which has a tendency to extend upwardly. The rectangular portion 1 of the frame is provided with a downwardly projecting extension 74 to which is secured, by bolts 75, an insulating block 76. Projecting forwardly from the insulating block 76 are four studs 77 which are provided at their ends with contact portions 78. The rear ends of the studs 77 which pass through the insulating block 76 are screw-threaded and carry nuts 79 which bear against the rear face of the insulating block and secure said studs thereto. The studs 77 are arranged in pairs, one pair being arranged directly beneath the other. The plunger 12 carries a downwardly extending tail rod 80. Mounted on the tail rod 80 is an insulating tube 81. At opposite ends of the tube 81 are annular insulating disks 82. The tube 81 is retained

on the tail rod 80 by a nut 83. Mounted on the insulating tube 81 are two contact disks 84 between which is interposed a coil spring 85. The coil spring bears against the insulating disks 86 interposed between the ends thereof and the disks 84. The disks 84 are arranged between the pairs of contact studs 77 so that when the plunger 12 is in its lowermost position the lower disk 84 will electrically connect the lower set of studs 77, while the upper disk 84 will electrically connect the upper pair of studs 77 when the plunger 12 is raised.

The switches just described are adapted to control auxiliary circuits. For instance, they may be employed to cut in a resistance in series with the winding 6 when the switch is closed, or may be employed to control the circuit of the operating winding of another switch.

The various parts of this contactor may be readily removed and replaced. For instance, to remove the arm 17, it is only necessary to detach the conductor 27 and the spring 24 therefrom, remove the pin 19 and then pull said arm straight out. By removing the rod 37 and disconnecting the terminal of the blow-out coil the insulating block 36 is permitted to slide freely in the grooves 35 of the frame and may be readily withdrawn therefrom, thereby removing the frame 39 bodily. After the switch arm and the insulating block 36 have been removed, the nut 83 may be detached from the tail rod 80 of the plunger 12 and then said plunger and the plug 9 withdrawn vertically from the winding 6. As soon as the plunger and plug have been withdrawn, the winding 6 may be removed from the rectangular portion of the frame. The parts may be as easily assembled by replacing the same in an inverse order to that just described.

Having thus described my invention what I claim as new and desire to secure by Letters Patent is:

1. In an electric switch, the combination with a frame having parallel upwardly extending portions, an insulating block supported between said upwardly extending portions of the frame and detachably secured thereto, a stationary contact carried by said insulating block, a switch arm arranged between said upwardly extending portions of the frame and adapted to engage said stationary contact, and an electromagnetic winding mounted in said frame beneath said switch and having a plunger for actuating said switch.

2. In an electric switch, the combination with a frame having a pair of parallel upwardly extending portions, of an insulating block fitting in grooves in said upright portions of said frame, means for securing said insulating block in place, contacts carried by said insulating block, a switch arm arranged

between said upright portions of said frame and adapted to be moved into engagement with said stationary contact, and an electromagnetic winding mounted in said frame, beneath said arm, and having a movable plunger for actuating said arm.

3. In an electric switch, the combination with a frame having a pair of parallel upwardly extending members, of an insulating block fitting in grooves in said members, detachable means securing said insulating block in position, a laminated main contact and a carbon contact carried by said insulating block, a switch arm arranged between the parallel members of said frame and carrying contacts adapted to engage the contacts carried by said insulating block, and an electromagnetic winding mounted in said frame for actuating said switch arm.

4. In an electric switch, the combination with a frame having a pair of upright members, of an insulating block fitting in grooves in said members, detachable means for securing said block in position, a contact holder carried by said block, a reversible laminated main contact adjustably mounted in said holder, a switch arm arranged between the upright members of said frame, and an electromagnetic winding mounted in said frame for actuating said switch arm.

5. In an electric switch the combination with a frame having two parallel upright members, of a switch arm arranged between said upright members, a pivot for said switch arm supported by said upright members, said switch arm having a notched portion for engaging said pivot, a solenoid mounted in said frame and having a movable core engaging said switch arm intermediate of its ends, the end of said core being rounded and fitting into a rounded recess in said switch arm, means for holding the notched portion of said switch arm in engagement with said pivot, contacts carried by said switch arm, an insulating block arranged above said switch arm and detachably secured to the upright members of said frame, and contacts carried by said insulating block and arranged to be engaged by the contacts carried by said switch arm.

6. In an electric switch, the combination with a frame having a pair of parallel upright members, an insulating block fitting in grooves in said upright members of said frame, detachable means for securing said insulating block in position, a main contact and an arcing contact carried by said insulating block, a switch arm arranged between the upright members of said frame, a pivot supported by said upright members of said frame, said switch arm having a notched portion for engaging said pivot, a solenoid mounted in said frame and having a movable core for supporting said switch arm intermediate of its ends, the end of said

core fitting into a recess in said switch arm, a spring connecting one end of said switch arm to said frame for maintaining the notched portion of said switch arm in engagement with said pivot, and contacts carried by said switch arm for engaging the contacts carried by said insulating block.

7. In an electric switch, in combination, a supporting frame, a solenoid mounted with-
in said frame, a switch arm supported by said frame above said solenoid and adapted to be actuated thereby, a relatively stationary contact arranged above and adapted to be engaged by said switch arm, a horizon-

tally disposed blow-out magnet mounted on 15
said frame below said switch and vertically disposed upwardly projecting pole pieces for said blow-out magnet disposed on opposite sides of said switch arm and said stationary contact.

20
In witness whereof, I have hereunto subscribed my name in the presence of two witnesses.

GEORGE BAEHR.
